UNITED STATES PATENT OFFICE.

BENJAMIN P. FORTIN, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,023,788.

Specification of Letters Patent. Patented Apr. 16, 1912.

Application filed October 21, 1910. Serial No. 588,233.

To all whom it may concern:

Be it known that I, BENJAMIN P. FORTIN, a citizen of the United States, residing in Hartford, in the county of Hartford and 5 State of Connecticut, have invented certain new and useful Improvements in Type-Writing Machines, of which the following is a specification.

The present invention relates to mechanism for back spacing the carriage of a type-writing machine by means of a key or similar device, so that upon each operation of the key the carriage may be moved back a definite distance, ordinarily a single space, 10 and thereupon be arrested. In mechanism of this class, there is ordinarily provided a dog which is normally disengaged from the carriage rack but which, when the back spacing key is operated, first moves into engagement with the rack and then moves back with the rack a single space. Stops, also actuated from the key, are usually provided for engaging the rack from above when the key is operated to prevent the rack from riding over the dog and thus being overthrown by reason of the momentum of the carriage; 15 and for holding the escapement wheel against movement during the back spacing operation.

One object of the present invention is a simplified means for actuating the back spacing dog, to the end that a single element may effect both the rack-engaging movement of the dog and the movement of the 20 dog with the carriage.

Another object of the invention is the elimination of unnecessary parts by operating the stop which prevents displacement and overthrow of the carriage, and the stop 25 which prevents movement of the escapement wheel, both from a single element, preferably the element which directly actuates the dog, so that these stops are brought to effective position at the proper time.

The invention in general has for its object 30 to simplify and render more certain and positive the operation of mechanism of this class.

The above and other specific objects and 35 features of the invention will presently and more fully appear in connection with the accompanying drawings in which—

Figure 1 is a view in perspective of so 40 much of the mechanism of the typewriting machine as relates to the present invention.

Fig. 2 is an enlarged view in front elevation of the mechanism which is operated from the back spacing key, the parts being shown in normal position. Fig. 3 is a view of the parts shown in Fig. 2 at the end of the 45 back spacing movement, before the key is released. Fig. 4 is a view similar to Fig. 2 with the parts in the position assumed when the back spacing dog has been brought to the rack, but before the dog has been moved 50 back with the rack. Fig. 5 is a detail perspective view showing more clearly the means by which the stops for the rack and escapement wheel are operated.

The carriage of the typewriter includes 55 a rack which is indicated at 1. This rack is supported on arms 2 pivoted at 3 to the frame of the carriage in a well known manner. One of the arms 2 is extended beyond the pivot to form a release key lever 4 for 60 swinging the rack upward by means of the arms 2 to disengage the rack from the pinion 5 which forms part of the escapement mechanism. The carriage is driven from the usual spring drum by means of a strap connection. The usual escapement wheel 6 and dog 6^a control the step-by-step or letter feed 65 movement of the carriage. The pinion 5 which normally engages the rack, is loosely mounted on the stud 5^a to which the escapement wheel is fixed. A pawl 7 pivotally attached to the face of the escapement wheel 6 is held against the pinion 5 by means of a spring 8, in such manner that the pinion is 70 locked to the escapement wheel to be controlled by the latter during the advance 75 movement of the carriage. During the back spacing movement of the carriage rack, however, the teeth of the pinion pass idly over the pawl, and the carriage moves independently of the escapement wheel. The carriage is back spaced by means of a dog 9 80 operated from a back spacing key 10, on a key lever 11, pivoted at 12 to the frame A. The lever 11 connects, by means of a link 85 13, with the arm 14 of a lever pivoted at 15 to a bracket 22 on the frame. The lever pivoted at 15 has an arm 16 which extends vertically and is then off-set horizontally, and at its end engages by means of slot 17^a, 90 a pin 17 in a lever 18. The lever 18 is pivoted at 19 to a bracket 20, which in turn is secured at 21 to the bracket 22 of the frame. The bracket 20 has an arm 23 (see Fig. 5) carrying a stud 24 which forms an attachment 95 100 105 110

for the dog 9 to the rocker. The dog 9 is slotted at 25 so that the dog may have not only a rocking movement but a longitudinal movement on the stud 24. Also pivotally mounted on the stud 24 is a lever having an arm 26 at the end of which is a tooth or detent 27 turned at right angles to the face of the arm 26 to extend over the rack 1, so that when the arm is depressed, the rack 10 may be engaged on its upper surface and held down by the detent 27, as hereinafter to be described. The arm 26 also carries a tooth or detent 28 extending rearwardly at right angles to the arm 26, so that, when 15 arm 26 is depressed, detent 28 may engage the escapement wheel 6 to prevent movement of the latter during the back spacing operation.

The dog 9 carries a pin 29 engaging the lever 18, so that the dog may be actuated by the lever 18 when the latter is moved by the lever 16, through the pin and slot connection 17-17^a, upon operation of the back spacing key. The lever 18 at its upper end 25 has two teeth or detents 30 and 31, somewhat spaced one from the other, and connected by a cam surface 32 against which bears the pin 29 of the dog 9. The inclination of the surface 32 is from the tooth 30 upward to the stop 31, so that when the lever 18 is rocked clockwise, (looking from the front), the engagement of the cam surface with the pin 29 causes the dog to be lifted or swung upward around its pivot 24 35 from the position shown in Fig. 2 to the position shown in Fig. 4, thus to be brought into engagement with the rack 1. The lever, of which the arm 26 is a portion, has also below its pivot 24 a second arm 33 extending to the right and terminating in a cam 34 formed by its upper surface. Pin 17 carried by the lever 18, and by means of which the lever 18 is connected to the lever 16, extends beyond the rear surface of the 40 lever 18 to permit it to be engaged by the cam 34, as shown in the various figures. When the lever 18 is rocked to the right by the lever 16, the pin 17, by engagement with the cam 34, after a sufficient movement of 45 the lever 18, causes the lever 26-33 to be rocked around its pivot 24 to bring the detent or tooth 27 down against the rack and to bring the detent or tooth 28 into engagement with the escapement wheel. As 50 shown in Fig. 4 the movement of the lever 18 in bringing the dog 9 to the rack, does not move the pin 17 sufficiently over the cam 34 to bring the detents 27 and 28 into engagement with the rack and escapement 55 wheel respectively. Further movement of the lever 18 to the right from the position shown in Fig. 4 to the position shown in Fig. 2, causes the arm 26 to bring detents 27 and 28 to the rack and wheel, respectively. 60 The movement of the lever 18 beyond the

position shown in Fig. 4, causes the detent 30, by engagement with the pin 29, to carry the dog 9 bodily to the right; the slot 25 permitting of this movement. As the dog 9 moves to the right with the carriage rack, 70 the detent 27 approaches the rack. When the dog has completed its prescribed throw, the detent is in engagement with the rack. The rack cannot then rise out of engagement with the dog, and thus be overthrown. 75 It must stop when the dog stops. At Fig. 3, the pin 17 is held at the upper end of the slot 17^a in the lever 16, and is at the uppermost point of the cam 34. The lever arm 26 is at this time depressed to its lowest position. The lever 26-33 is thus locked against movement by the lever 16 on the one hand, and by the rack on the other hand. The throw of the dog is positively determined by the engagement of the left 80 hand end wall of the slot 25, in the dog, with the pivot pin 24 on the lever arm 26. When the back-spacing key 10 is released, the levers 16, 14, 13, 11, and the key, are returned to normal position by a coil spring 90 36 which at one end engages the frame, and at the other end engages the lever arm 16. The lever arm 16 in returning to normal position carries with it the lever 18. The return movement of the cam 32 permits the 95 dog 9 to drop away from the rack 1; and, the tooth 31 on the lever 18, by engagement with the pin 29 on the dog, slides the dog back longitudinally until its pivot pin 24 engages the right hand end of the slot 25, 100 when the dog is again in normal position. The spring 36 acting through the lever 16, lever 18, pin 29, dog 9 and pin 24 returns the rocker to normal position, as determined by a stop on the frame. The tooth 105 31 by engagement with the pin 29 acts as a stop to determine the normal position of the key lever system. A spring 37 attached at one end to the lever 26-33 and at the other end to the lever 18 is put under tension 110 when these levers are moved on the depression of the key 10; and, when the key is released, so that the pin 17 is moved back over the cam 34 by the lever 18, the spring 37 draws the lever 26-33 to normal position, 115 thus removing the stops 27 and 28 from the rack and escapement mechanism, respectively.

A brief summary of the operation of the parts is as follows: Depression of the key 120 10 rocks the lever 11, lifts the link or the thrust rod 13, and rocks the lever 14-16 to the right against the action of the spring 36. The lever arm 16 in this movement, rocks the lever 18 around its pivot 19. During 125 the first part of its movement, the lever 18 by virtue of the cam 32 swings the dog up around its pivot 24 into engagement with the rack. Further movement of the lever 18 causes the tooth 30 by engagement with 130

the pin 29, to shift the dog bodily longitudinally on its pivot pin 24, thus back-spacing the rack. During this bodily shift of the dog 9, pin 17, by engagement with the cam 34 of the lever 26-33, rocks that lever against the action of the spring 37 until the detent 27 engages the rack 1 and the detent 28 engages escapement wheel 6. When the detent 27 engages the rack, further movement of the lever 26-33 is impossible. The movement of the rocker is stopped by the frame. The throw of the dog with the rack is stopped by the pin 24 on the rocker engaging the end wall of the slot 25. The rack is locked between the dog and the detent 27 and therefore cannot be overthrown. On release of the key, the spring 36 returns the key lever system and the rocker; and the spring 37 returns the stop lever 26-33, as heretofore described.

The structure shown and described is capable of considerable modification within the scope of the invention. Portions of the improvements may be used without others.

Having thus described my invention, I claim:

1. In a typewriting machine, a carriage, a rack on the carriage, escapement mechanism coöperating with the rack to control the feed of the carriage, a dog movable into and out of engagement with the rack and movable with the rack to back space the same, a lever having a cam thereon for moving the dog into engagement with the rack, means for operating the lever, and means on the lever for moving the dog with the rack when the dog and rack are in engagement.

2. In a typewriting machine, a carriage, a rack on the carriage, escapement mechanism coöperating with the rack to control the feed of the carriage, a dog movable into and out of engagement with the rack and movable with the rack to back space the same, a lever having a cam for moving the dog into engagement with the rack, said lever having also a detent for engaging and moving the dog with the rack after the dog has been brought to the rack by the cam, and means for operating the lever.

3. In a typewriting machine, a carriage, a rack on the carriage, escapement mechanism coöperating with the rack to control the feed of the carriage, a dog movable into and out of engagement with the rack and movable with the rack to back space the same, a lever having a cam for moving the dog into engagement with the rack, said lever having also means for engaging and moving the dog with the rack after the dog has been brought to the rack by the cam, and means for operating the lever.

4. In a typewriting machine, a carriage, a rack on the carriage, escapement mechanism coöperating with the rack to control

the feed of the carriage, a dog movable into and out of engagement with the rack and movable with the rack to back space the same, a pivoted arm or lever on which the dog is pivotally mounted to swing into and out of engagement with the rack, the dog having also longitudinal movement on said arm or lever to move with the rack during the back spacing operation, and means for actuating the dog.

5. In a typewriting machine, a carriage, a rack on the carriage, escapement mechanism coöperating with the rack to control the feed of the carriage, a dog movable into and out of engagement with the rack and movable with the rack to back space the same, a support for the dog, the dog having a single pin and slot engagement with its support whereby it may swing on its support into engagement with the rack and may thereafter by virtue of the slot move longitudinally on its support with the rack in back spacing, and means for actuating the dog.

6. In a typewriting machine, a carriage, a rack on the carriage, escapement mechanism coöperating with the rack to control the feed of the carriage, a dog movable into and out of engagement with the rack and movable with the rack to back space the same, a support for the dog, the dog having a single pin and slot engagement with its support whereby it may swing on its support into engagement with the rack and may thereafter by virtue of the slot move longitudinally on its support with the rack in back spacing, the end wall of the slot serving, by engagement with the pin, as a stop to limit the throw of the dog with the rack, and means for actuating the dog.

7. In a typewriting machine, a carriage, a rack on the carriage, escapement mechanism coöperating with the rack to control the feed of the carriage, a dog movable into and out of engagement with the rack and movable with the rack to back space the same, a support for the dog, the dog having a pin and slot engagement with its support whereby it may swing on its support into engagement with the rack and may thereafter by virtue of the slot move longitudinally on its support with the rack in back spacing, a lever engaging the dog to actuate the same, and means for actuating said lever.

8. In a typewriting machine, a carriage, a rack on the carriage, escapement mechanism coöperating with the rack to control the feed of the carriage, a dog movable into and out of engagement with the rack and movable with the rack to back space the same, a support for the dog, the dog having a pin and slot engagement with its support whereby it may swing on its support into engagement with the rack and may there-

after by virtue of the slot move longitudinally on its support with the rack in back spacing, a lever engaging the dog to actuate the same, the lever having a cam engagement with the dog to swing the dog to the rack, and having means for engaging and carrying the dog with the rack after the cam has caused the dog to engage the rack.

- 10 9. In a typewriting machine, a carriage, a rack on the carriage, escapement mechanism coöperating with the rack to control the feed of the carriage, a dog movable into and out of engagement with the rack and movable with the rack to back space the same, a lever-arm carrying a stop, and a cam for moving said lever arm to bring the stop into engagement with the rack to prevent movement of the rack away from the dog, and means for actuating said cam and dog.

10 10. In a typewriting machine, a carriage, a rack on the carriage, escapement mechanism coöperating with the rack to control the feed of the carriage, a dog movable into and out of engagement with the rack and movable with the rack to back space the same, a lever-arm carrying a stop, and a cam for moving said lever arm to bring the stop into engagement with the rack to prevent movement of the rack away from the dog, and a lever engaging said dog and said stop arm cam for actuating the same.

11. In a typewriting machine, a carriage, a rack on the carriage, escapement mechanism coöperating with the rack to control the feed of the carriage, a dog movable into and out of engagement with the rack and movable with the rack to back space the same, a lever carrying a stop, a cam on said stop lever whereby the stop lever is actuated to bring the stop into engagement with the rack to prevent movement of the rack away from the dog, a lever for actuating the dog, and means on said dog actuating lever for engaging the stop lever cam to actuate the latter.

12. In a typewriting machine, a carriage, a rack on the carriage, escapement mechanism coöperating with the rack to control the feed of the carriage, a dog movable into and out of engagement with the rack and movable with the rack to back space the same, a lever carrying a stop, a cam on said stop lever whereby the stop lever is actuated to bring the stop into engagement with the rack to prevent movement of the rack away from the dog, a lever for actuating the dog, a cam on said dog actuating lever to move the dog into engagement with the rack, and a pin on said dog actuating lever for engaging the cam on the stop lever to actuate the latter.

13. In a typewriting machine, a carriage, a rack on the carriage, escapement mecha-

nism coöperating with the rack to control the feed of the carriage, a dog movable into and out of engagement with the rack and movable with the rack to back space the same, a lever carrying a stop, a cam on said stop lever whereby the stop lever is actuated to bring the stop into engagement with the rack to prevent movement of the rack away from the dog, a lever for actuating the dog, a cam on said dog actuating lever to move the dog into engagement with the rack, a pin on said dog actuating lever for engaging the cam on the stop lever to actuate the latter, and a key operated lever engaging said pin to move said dog actuating lever.

14. In a typewriting machine, a carriage, a rack on the carriage, escapement mechanism coöperating with the rack to control the feed of the carriage, a dog movable into and out of engagement with the rack and movable with the rack to back space the same, said dog being mounted to swing on its support into and out of engagement with the rack and to move longitudinally on its support with the rack, a lever carrying a cam to swing the dog and a detent to shift the dog longitudinally, a lever carrying a stop movable into engagement with the rack to prevent shifting the rack away from the dog, and a cam on said stop lever engaged by said dog actuating lever to bring the stop to the rack when the dog is actuated.

15. In a typewriting machine, a carriage, a rack on the carriage, escapement mechanism coöperating with the rack to control the feed of the carriage, a dog movable into and out of engagement with the rack and movable with the rack to back space the same, said dog being mounted to swing on its support into and out of engagement with the rack and to move longitudinally on its support with the rack, a lever carrying a cam to swing the dog and a detent to shift the dog longitudinally, a lever carrying a stop movable into engagement with the rack to prevent shifting the rack away from the dog, and a cam on said stop lever engaged by said dog actuating lever to bring the stop to the rack after the dog has engaged the rack.

16. In a typewriting machine, a carriage, a rack on the carriage, escapement mechanism coöperating with the rack to control the feed of the carriage, a dog movable into and out of engagement with the rack and movable with the rack to back space the same, said dog being mounted to swing on its support into and out of engagement with the rack and to move longitudinally on its support with the rack, a lever carrying a cam to swing the dog and a detent to shift the dog longitudinally, a lever carrying a stop movable into engagement with the rack to prevent shifting the rack away from the dog.

dog, and a cam on said stop lever engaged by said dog actuating lever, said last-named cam acting, during the longitudinal shift of the dog, to bring the stop to the

5 rack.

17. In a typewriting machine, a carriage, a rack on the carriage, escapement mechanism coöperating with the rack to control the feed of the carriage, a dog movable into and out of engagement with the rack and movable with the rack to back space the same, a lever arm carrying a stop, and a cam for moving said lever arm to bring the stop into engagement with the escapement mechanism, to prevent back movement of the latter, and means for actuating the dog and cam.

18. In a typewriting machine, a carriage, a rack on the carriage, escapement mechanism coöperating with the rack to control the feed of the carriage, a dog movable into and out of engagement with the rack and movable with the rack to back space the same, a lever arm carrying a stop, and a cam for moving said lever arm to bring the stop into engagement with the escapement mechanism, to prevent back movement of the latter, and means for actuating the dog and cam.

30 19. In a typewriting machine, a carriage, a rack on the carriage, escapement mechanism coöperating with the rack to control the feed of the carriage, a dog movable into and out of engagement with the rack and movable with the rack to back space the same, a lever carrying a stop, a cam on said

stop lever whereby the stop lever is actuated to bring the stop into engagement with the rack to prevent movement of the rack 40 away from the dog, a lever for actuating the dog, a cam on said dog actuating lever to move the dog into engagement with the rack, and a pin on said dog actuating lever for engaging the cam on the stop lever to 45 actuate the latter; said stop lever carrying a second stop to engage the escapement mechanism when said lever is actuated.

20. In a typewriting machine, a carriage, a rack on the carriage, escapement mechanism coöperating with the rack to control the feed of the carriage, a dog movable into and out of engagement with the rack and movable with the rack to back space the same, a lever for operating the dog, a stop 55 arm for preventing movement of the rack away from the dog, and a spring connecting the stop arm and dog actuating lever to return the stop arm to normal position.

21. In a typewriting machine, a carriage, a rack on the carriage, escapement mechanism coöperating with the rack to control the feed of the carriage, a dog movable into and out of engagement with the rack and movable with the rack to back space the 65 same, a lever for operating the dog, a stop arm for holding the escapement mechanism, and a spring connecting the stop arm and dog actuating lever to return the stop arm to normal position.

BENJAMIN P. FORTIN.
